UNITED STATES PATENT OFFICE.

WILLIAM D. BUTT, OF KANSAS CITY, MISSOURI.

ADVERTISING DEVICE.

SPECIFICATION forming part of Letters Patent No. 706,525, dated August 12, 1902.

Application filed December 4, 1901. Serial No. 84,599. (No model.)

To all whom it may concern:

Be it known that I, WILLIAM D. BUTT, a citizen of the United States of America, residing at Kansas City, in the county of Jackson 5 and State of Missouri, have invented certain new and useful Improvements in Advertising Devices; and I do hereby declare that the following is a full, clear, and exact description of the invention, such as will enable others to 10 make and use the same, reference being had to the accompanying drawings, forming a part of this specification.

The object of my invention is, first, an advertising-sign which forms the background to 15 the deflected rays of light; second, to secure the sliding panels of the frame from accidental removal, and, third, to enable the frame to be readily attached to and removed from a fixed foot-support.

20 The invention consists in the novel construction and combination of parts, such as will be first fully described and then specifically pointed out in the claims.

In the drawings, Figure 1 is a view in perspective of the novel advertising-case, showing the stationary post and foot-support and the securing devices on the case. Fig. 2 is a view of the top of the advertising-case. Fig. 3 is a view of the bottom of the advertising- 25 case looking upward. Fig. 4 is a vertical sectional view of the advertising-case, showing the panels within the side-frames. Fig. 5 is a view of the rear end of the case.

Similar letters of reference indicate corresponding parts in all the figures of the drawings.

Referring to the drawings, A represents a longitudinal case for the reception of advertising-panels. The sides of the case consist 30 of the parallel frames $a\ a$, having the transverse openings $a^x\ a^x$, which are arranged a short distance apart, and with the upper longitudinal edges of said frames is connected the horizontal plate a' , which forms the top 35 to said case and extends the length of said frames. With the lower longitudinal edges of said frames is connected a plate a^2 , which forms the bottom of said case and which also extends the length of said frames. The rear 40 end of the case A is closed by a vertical plate a^3 , connected with the ends of said frames

a , and which end is secured, as hereinafter described, to the proper support.

Within the frame A are sliding transparent panels B B, which are slightly smaller in 55 length and width than the case A and are inserted within the forward end of the said case close in position to the inner side of the said frames $a\ a$.

The forward end of case A is inclosed by an 60 outwardly-curved plate C, with the upper and lower ends of which plate are secured rigidly and at a point intermediate the vertical edges of said plate the outer ends of the horizontal bars $c\ c$, the inner ends of which bars are piv- 65 otally connected by the pivots $c'\ c'$ with the outer surfaces of the respective top and bottom plates $a'\ a'$ a short distance inwardly from the forward end of the case.

In the upper plate c , a short distance from 70 the pivot c' in the direction of the end of said plate connected with plate C, is a perforation c^3 , in which is inserted a lock-pin c^4 , which enters a similar perforation in the top a' of the case and prevents the lateral movement 75 of plate C. Upon the rear end a^3 of case A and near the lower part of said case is a wedge-shaped lug a^8 .

With the under surface of the bottom a^2 of the case A is connected rigidly the upper edge 80 of a longitudinal pendent sign-plate D, the lower edge of which plate extends downwardly a short distance below the bottom of said case, and upon the vertical side of the plate D are printed or otherwise affixed the letters d , 85 which indicate the names of the street. The rear end of plate D extends to the line of the rear end of the case A, and from said end is a downward extension d^2 , which is secured by a screw d^3 to the post F. 90

Within the case A is an incandescent lamp E, the conductors $e\ e$ from which extend upwardly through the top a' of the case and are connected with the usual electric-light wires. (Not shown.) In the bottom a^2 of the case A 95 are the perforations a^6 , which are arranged in series in the longitudinal direction of the case and between a vertical line extending upon the surfaces of the sides of the plate D and the panels B B. 100

F represents an ordinary pole or standard for supporting electric-light wires, and G is a

rod or bar, one end of which is driven within the post, and the other end extends horizontally therefrom, so as to form a foot-support in climbing the pole, the outer end g of which is bent at right angles and extended upwardly a short distance.

Upon the top a' of case A, equidistant from its forward and rear ends, is a lug h , extending transversely to said case, in which is a 10 perforation h' .

Upon the rear end a^3 of case A and near the top of said case is a transverse plate I, which is integral with the rear end a^3 and extends a short distance above the line of the 15 top a' of case A. In the upper edge of the plate I, equidistant from the ends of said plate, is a notch i , which extends downwardly nearly to the top a' of case A. From the sides of notch i extend forwardly the lugs $i' i'$, 20 which lugs are perforated transversely at i^2 . Through the perforations $i^2 i^2$ extends a screw-bolt i^4 , upon one end of which is a head i^5 and upon the other end a nut i^6 . In the attachment of the case A to the plate P the 25 bolt i^4 is removed from the lugs $i' i'$. The curved end of the rod G on the plate F is then inserted within the opening h' of the lug h . The rear end of the case is then raised in position, the inner end of the rod G passing 30 between the lugs $i' i'$ and coming into contact with the top a' of case A. The bolt i^4 is then inserted within the perforation i^2 in the lugs and above the rod G, thereby supporting said rear end of said case, the lug 35 a^8 upon which is forced into the post F.

In removing the panels B from the case the lock-pin c^4 is first removed from the pivoted plate c and the plate C vibrated laterally, so as to expose the panels. After the removal 40 of the panel the plate C is moved into position and secured, as before. The rays from

the incandescent light E pass downwardly through the perforations a^6 in the bottom a^2 of case A past the sign or letter d , which are now readily seen in the rays as they illuminate the full surface of the sign. 45

Such modifications may be employed as are within the scope of the invention.

Having fully described my invention, what I now claim as new, and desire to secure by 50 Letters Patent, is—

1. In advertising devices a case, a pendent sign connected with the under surface of the bottom of said case, said bottom having perforations and a luminous body within said 55 case.

2. An advertising-case, a suspension rod or bolt, a lug connecting the forward end of the case with the said rod, and a notched plate upon the rear end of said case, perforate 60 lugs extending from the forward sides of said plate, and a bolt extending through said lugs.

3. An advertising-case and a pendent sign connected with the bottom of said case, a standard, a suspension-rod upon said standard for said case, a lug connecting the forward end of said case with said rod, and a downward extension of said sign connected with said standard. 65

4. A structural advertising device, comprising a penetrable standard, and a suspension-rod upon said standard, an advertising-sign body, a perforate lug on said body connecting said case with said rod, a projection upon the rear end of said sign-body, and a 70 clamping device upon said sign-body acting to force the projection into said standard. 75
